US00D873822S

(12) **United States Design Patent** (10) **Patent No.:** **US D873,822 S**
(45) **Date of Patent:** **** Jan. 28, 2020**

(54) **IMAGE DISPLAY**

(71) Applicant: **Sakai Display Products Corporation**,
Sakai-shi, Osaka (JP)

(72) Inventors: **Tomohiro Asamizu**, Sakai (JP); **Yusuke Miyake**, Sakai (JP); **Noriaki Miyoshi**, Sakai (JP); **Tomoaki Oya**, Sakai (JP)

(73) Assignee: **Sakai Display Products Corporation**,
Sakai-shi, Osaka (JP)

(**) Term: **15 Years**

(21) Appl. No.: **29/629,630**

(22) Filed: **Dec. 14, 2017**

Related U.S. Application Data

(63) Continuation-in-part of application No. 29/512,886,
filed on Dec. 23, 2014, now abandoned.

(30) **Foreign Application Priority Data**

CLAIM

The ornamental design for image display, as shown and described.

DESCRIPTION

FIG. 1 is a front view;
FIG. 2 is a back view;
FIG. 3 is a left side view;
FIG. 4 is a right side view;
FIG. 5 is a top view;
FIG. 6 is a bottom view;
FIG. 7 is a top, front, right perspective view;
FIG. 8 is an enlarged, front, perspective view of FIG. 7, taken along the annotation line 8-8;
FIG. 9 is an enlarged, front, perspective view of FIG. 7, taken along the annotation line 9-9;
FIG. 10 is a top, front, left perspective view;
FIG. 11 is an enlarged, front, perspective view of FIG. 10, taken along the annotation line 11-11; and,
FIG. 12 is a top, rear, left perspective view.

(Continued)

The broken lines, shown in the drawings, are for annotation purposes and indicate the point at which the enlarged views are cut off. None of the broken lines form part of the claimed design.

1 Claim, 12 Drawing Sheets
